ELECTRICALLY HEATED CHICKEN BROODER

Filed May 4, 1942

FIG. 1

FIG. 2

Inventor

ALBERT L. KAYSING

By: *Ben V. Zillman*
Attorney

UNITED STATES PATENT OFFICE

2,327,800

ELECTRICALLY HEATED CHICKEN
BROODER

Albert L. Kaysing, St. Louis, Mo., assignor to
J. A. Smith Company, St. Louis, Mo., a partnership composed of Albert L. Kaysing, T. D. Shaffer, and S. B. Margulis

Application May 4, 1942, Serial No. 441,639

3 Claims. (Cl. 219—35)

The instant invention relates to improvements in chicken brooders, and more particularly to such brooders that are electrically heated so that substantially all parts of the chick-receiving hover are warmed to approximately the same temperature.

The invention has among its objects the production of such a device that will be easy to build and operate, low in cost, both in the materials employed and in the maintenance of the brooder, that may be easily cleaned, neat and attractive in appearance, and otherwise satisfactory and efficient for use wherever deemed applicable.

One of the principal objects of my invention is to so construct the various parts of the brooder that it will accommodate the maximum number of chicks for its size, and wherein the chick-receiving chamber of the same may be adjusted from time to time during the stay of the chicks in the chamber, to provide increasing head-room for the growing chicks, and so that substantially none of the heat is dissipated in heating larger spaces than is being used at the immediate time.

An added object of my invention is to provide, in a brooder of the kind described, a compact and serviceable electrical heating unit that is self-contained so as to be easily and readily mounted into the chick-receiving hover for operation of the brooder.

A further object of the invention is so to construct the heating unit that it may be mounted on the under side of the roof of the chick-receiving hover and may be adjusted from above said roof by simple manipulation of a screw driver applied to the thermostat controlling said heating unit.

An added object is to so construct the aforesaid device, that the heating element is enclosed within a radiating and convection tube so as to prevent injury to any of the chicks that may contact the tube, there being a downwardly and outwardly flared deflector mounted above and in spaced relation to said tube, a metal plate carrying said deflector and tube and extending far beyond the bounding edges of either of the latter so as to act as an auxiliary deflector to insure heating the far corners of the hover, said plate being mounted to the lower face of the roof of said hover and forming an integral unit of the roof member of the hover and the various heater parts so that all may be moved truly unitary whenever it is desired to adjust the size of the head-room of the hover.

Many other objects and advantages of the construction herein shown and described, and the

uses mentioned, will be obvious to those skilled in the art to which this invention appertains, as will be apparent from the disclosures herein given.

To this end, my invention consists in the novel construction, arrangement and combination of parts herein shown and described, as will be more clearly pointed out in the following specification.

In the drawing, wherein like reference numerals indicate like or corresponding parts throughout the views,

Figure 1 is a perspective side view of my improved device, with the floor of the exercise yard removed; and

Figure 2 is a longitudinal cross-sectional view of the same, as mounted on a table or platform, and showing only the adjacent portion of the exercise yard.

Referring more particularly to the drawing, wherein I have illustrated a preferred embodiment of my invention, there is shown a brooder adapted to comfortably receive and shelter a number of recently hatched chicks, and to maintain them sufficiently warmed therein for the required number of weeks that it will take for them to reach that stage of growth for marketing them or otherwise disposing of them.

A frame consisting of a pair of opposed and spaced end walls 1—2 connected by opposed spaced side walls 3—3, forms a substantially rectangular supporting structure for the remaining parts of the device. At a point somewhere intermediate the length of the device there is a movable end closure in the form of a door or gate 4, to define the limits of the chick-warming hover.

Although this brooder may be mounted out of doors, or within a room, I have preferred to show the same as being in the latter arrangement, and similarly the brooder is shown as mounted directly on a platform, table or other supporting structure, although it may be mounted directly spaced above any floor, by legs or similar elements.

If desired, a floor-supporting frame 5 may be secured within the bounding walls of the brooder, as by constructing it to come flush with the bottom edges of the latter as shown, and extending for substantially the full length and width of the frame parts 1, 2 and 3—3.

In order that the brooder be kept as clean and sanitary as possible, I have found that the floors should be removable, and to this end I have inserted a floor comprising a rectangular frame 6,

of a size to neatly fit within the bottom of the chick-receiving hover or chamber between the side walls 3-3 and the wall 1 and door 4, and to the top side of the frame 6 I have provided a covering of suitable mesh and strength of wire screening 7.

The exercise yard may be similarly provided with removable floors, by one or more sections of flooring similar to that just described for the hover, the frame portion 8 and screening 9 of such exercise yard floor portions or sections being shown in Fig. 2.

Obviously, whenever any floor section is desired to be taken up, for cleaning or disinfecting therebelow, it may be removed without difficulty—simply by lifting it up. Replacement is just as simple.

A cover member or top 10, fastened to a pair of side walls 11-11 and end walls 12-12 comprise a rectangle of substantially the same size of the floor section 6, and is preferably detachably mounted on the open top of the chamber therebelow, as with side and end lugs 13.

A partition 14 is inserted to extend substantially horizontally across the receptacle, below said top 10, this partition thereby being common to the upper and lower chambers or hovers, 15 and 16 respectively, thus formed, being the floor of the upper hover and the roof of the lower hover. Its length is less than that of the hovers so as to provide an opening or air passageway 17 between the door 4 and the adjacent edge of the partition, and to permit of air movement between the upper and lower hovers therethrough.

Air vents 18 are provided through said partition, grouped adjacent the front and the rear edges of the latter, so as to provide slower passage of air between the hovers at said vents. The forward edge of the partition is provided with an overhanging or downwardly directed flange 19 therealong so as to direct heated air from the under side of the partition downwardly into the lower hover.

Inasmuch as the chicks remain in the brooder for quite a number of weeks until they are ready to be removed from such shelter, for marketing or other disposition, I have provided compensatory means to properly keep pace with the varying size of the chicks and to give them more headroom as they grow bigger. To this end, I have arranged the partition 14 to be adjustably raised from time to time, as needed.

A partition-supporting frame 20 is nailed or otherwise fixed to the side walls of the hover and may be detached therefrom and moved to a new position upwardly of its first position every few weeks or so; or additional frames 21 may be fixed to the said walls of the hover, spaced at any preferred distance from the lowermost frame 20, so that the partition may be lifted out and re-set to a higher position with utmost ease. In this manner, there is always presented the necessary space and head-room for the chicks within the lower hover, and no more space than is actually required at a given stage of growth of chicks need be heated.

The upper chamber 15, and what might be termed a pre-heated fresh air intake chamber or hover, is provided with vents 22 through its top.

A tubular element 23, open at both ends and provided with apertures 24 through its bounding wall, is supported at about the mid-portion of the lower hover or chamber 16, the lower end of

said tube being spaced above the floor section within said hover.

An electrically energized heating element 25 is fixed within said tube, and preferably spaced well within the confines of the latter so that there is a good air space between the element 25 and the tube wall, to prevent overheating said tube, this electrical element having an automatic thermostatic control 26 adjustably regulated at a selected operating temperature by means of the set screw 27 or the like, the electrical conductors to the heater and thermostatic circuit being indicated in the dotted lines in Fig. 2.

A substantially conical-shaped heat deflector 28 is mounted to be spaced above the top end of the tube element, as by the brackets 29, said deflector having its peripheral edge extending radially beyond the side wall of the tube, somewhat as shown. A large metal plate 30 is secured to the deflector 28 and the thermostat may be fixed to said plate, said plate extending to nearly adjacent the bounding edges of the under side of the partition 14. The plate 30 forms a rigid integral unit with the deflector, tube, heating element, and thermostat, so that all of the same, together with said partition, may be considered a unit inasmuch as the entire structure is demountable or removable as a unit, to the various head-room sizes of the lower hover.

The plate 30 is provided with an opening therethrough, and the adjusting screw 27 of the thermostat projects through said opening. The partition 14 is similarly provided with an opening 33 in substantially vertical alignment with the opening 35, so as to afford access to said screw from above the partition member, as with a screw driver or other suitable tool.

The heat from the element 25 is directed not only to warm the tube and the deflector thereabove, but a portion of the heat passes laterally through said tube and from its ends directly, while the deflector directs the heat impinged thereagainst downwardly and outwardly onto the backs of the chicks within the hover. The plate 30 acts as an auxiliary deflector for heat which it receives, and throws the same downwardly and into the areas adjacent the far corners of said hover.

The portion of the brooder shown to the right of the hovers may be used as an exercise yard and for feeding the chicks, the door 4 being provided with a hinge 37 for mounting it to the wall 12 of the hovers, and with latch means 31 to cooperate with means 32 on a cross bar 33 that extends between the opposed sides 3-3. Vents 34 may be provided through said walls 3-3 just below the uppermost or opened position of the door, in order to further insure proper ventilation while the door is maintained in its open or dotted line position shown.

Having thus described my invention, it is obvious that various immaterial modifications may be made in the same without departing from the spirit of my invention; hence I do not wish to be understood as limiting myself to the exact arrangement, construction, combination and form shown and described, or the uses mentioned, except as limited to the claims hereunto appended.

What I claim as new and desire to secure by Letters Patent is:

1. In a chick brooder, a housing; a removable, vertically adjustably mounted substantially horizontal partition therein, dividing said housing into an upper and a lower chamber; air vents

through said partition to permit air passage between said chambers; and an electrical heating device fixed to the under side of said partition to be moved as a unit together therewith, said device comprising a tube, a heating element fixed therein spaced from its side wall, a metal plate for attachment to the under side of said partition, and an outwardly flared downwardly directed flanged element fixed intermediate said plate and tube and spaced above the latter for directing the rising heat downwardly into the chamber and toward the lateral walls of the same.

2. In a chick brooder, a housing; a vertically adjustable substantially horizontal partition therein, dividing the housing into an upper and a lower chamber; air vents through said partition; and an electrical heating device fixed to the under side of said partition to be moved as a unit together therewith, said device comprising a tube, a heating element therein and spaced from the tube side wall, a heat deflector sheet at the under side of said partition, and an out-

wardly flared downwardly directed flanged element positioned intermediate said sheet and tube and spaced above the latter for directing the rising heat downwardly into the chamber and toward the lateral walls of the latter.

- 5 3. In a chick brooder, a vertically adjustable substantially horizontal partition dividing the same into superimposed upper and lower chambers and whereby the height of the lower chamber may be selectively varied; an electrical heating device carried at the under side of said partition as a unit movable therewith and comprising a tube, a heating element therein and spaced from the tube side wall, a heat deflector sheet fixed between said partition and tube, and an outwardly flared downwardly directed flanged element positioned intermediate said sheet and tube and spaced above the latter for directing heat downwardly into the lower chamber and toward the side walls of the latter.
